DESK SET

Carey Garfield Gregory, Los Angeles, Calif.

Application June 10, 1938, Serial No. 213,056

8 Claims. (Cl. 120—59)

My invention relates broadly to desk sets and more particularly to an improved construction of desk set operating upon the principle of hydrostatic pressure for feeding ink to a dip pen well.

One of the objects of my invention is to provide an improved construction of hydrostatic desk set which facilitates quantity production at relatively low cost.

Another object of my invention is to provide a construction of hydrostatic desk set formed from a minimum number of parts capable of being molded from a variety of synthetic materials.

Another object of my invention is to provide a construction of moldable desk set having a minimum number of parts with the pen receiving guide formed integrally with the molded structure of the desk set.

A still further object of my invention is to provide a construction of molded desk set in which certain of the parts interfit with each other telescopically forming an ink receiving receptacle into which a dip pen is adapted to be submerged.

Still another object of my invention is to provide a construction of desk set operative upon the hydrostatic principle in which the quantity of the ink supply in the receptacle into which a dip pen is adapted to be submerged is restricted in comparison with the quantity of ink supplied to the receptacle by the hydrostatic pressure.

Still another object of my invention is to provide a desk set having a minimum number of interengaging parts and in which the line of division of the parts may be wholly obscured in the process of manufacture of the parts and a unitary appearance imparted to the desk set for improving the esthetic qualities thereof.

A still further object of my invention is to provide a construction of molded desk set in which a pressure equalizing aperture is molded directly into that part of the desk set which also unites integrally with the pen receiving guide in the desk set.

Other and further objects of my invention reside in the improved construction of molded desk set as set forth more fully in the specification hereinafter following by reference to the accompanying drawings in which:

Figure 1 is a side elevation of a desk set constructed in accordance with my invention; Fig. 2 is a central vertical longitudinal sectional view of the desk set on an enlarged scale with parts broken away and showing certain of the parts in side elevation; Fig. 3 is a horizontal sectional view taken on line 3—3 of Fig. 2; Fig. 4 is a side

elevational view of the base of the desk set after completion of the baking and finishing treatment showing the parts appearing as a single unit; Fig. 5 is a vertical sectional view through the base of the desk set taken substantially on line 5—5 of Fig. 1; Fig. 6 is a cross-sectional view of the upper and lower portions of the base of the desk set illustrated in juxtaposition; Fig. 7 is a side elevational view with parts broken away and illustrated in section showing a modified form of the desk set of my invention; Fig. 8 is a central vertical longitudinal section taken through the desk set of Fig. 7 and shown on an enlarged scale with certain of the parts illustrated in side elevation; Fig. 9 is a horizontal sectional view taken on line 9—9 of Fig. 8; Fig. 10 is a vertical sectional view taken on line 10—10 of Fig. 9, the ink bottle being omitted for the sake of clearance; Fig. 11 is a vertical longitudinal sectional view taken through another modified form of desk set embodying my invention with certain of the parts broken away and with certain of the parts illustrated in side elevation; Fig. 12 is a horizontal section taken on line 12—12 of Fig. 11; Fig. 13 is a vertical sectional view taken on line 13—13 of Fig. 12; and Fig. 14 is a vertical sectional view showing parts of the base structure of the desk set illustrated in Figs. 11—13, in juxtaposition and illustrated on a somewhat reduced scale.

The improved desk set of my invention is the result of extended research and development in the art of desk sets operating upon the principle of hydrostatic pressure of the class set forth in my Patents 2,026,529, granted January 7, 1936 and 2,112,907, granted April 5, 1938.

In my improved construction of hydrostatic desk set, the parts are reduced in number by molding the principal parts integrally as a unit from synthetic moldable material. The pen receiving guide through which a dip pen is adapted to be inserted is molded integrally with the top portion of the molded base structure. I have found that it is wholly unnecessary to construct the guide for the dip pen independently of the base structure for in the improved arrangement of my invention the socket constituting the pen guide is integrally molded with the upper portion of the base structure. The pressure equalizing port is molded directly into the upper portion of the base structure. The central bore through which the threaded neck of the ink supply bottle extends is provided with screw threads molded directly into the material of the upper portion of the base and all bushings or threaded inserts or gaskets dispensed with in establishing con-

nexion between the ink supply bottle and the upper portion of the base.

The quantity of ink in the pool or reservoir into which the point of a dip pen is adapted to be inserted is restricted in the improved construction of my invention so that a smaller quantity of ink is consumed than in hydrostatic desk sets of previous constructions and the smaller quantity of ink maintained in better writing condition than is the case when a larger quantity of ink is maintained in the ink pool. The parts of the desk set are molded from synthetic material of various kinds such as Resinox, Tenite, Porcelain, Bakelite and other phenol condensation products. I may mold the parts of the desk set from glass or other transparent material. Two principal parts are required; that is, the lower base portion which receives the ink supply and the upper base portion which provides telescopic interengagement with the lower base portion. In constructions where the division between the upper and lower portions of the base is substantially transverse, the exterior cylindrical wall is treated with a fusible material which enters the transverse division between the upper and lower portions of the base and after being fused and baked, presents a substantially invisible seam which when coated presents an esthetic and ornamental appearance. In arrangements where the upper and lower portions of the base telescopically engage for substantially the entire depth of the base, the cemented joint is entirely invisible when the base is viewed in side elevation. The restricted ink pool into which the dip pen may be inserted may be molded integrally with the lower portion of the base or may be in the form of an eccentrically mounted receptacle confined within the base. The principles of my invention may be carried out in various embodiments and the forms set forth herein are to be considered in the illustrative sense and not in the limiting sense.

Referring to the drawings in detail, reference character 1 indicates generally the base of the desk set of my invention comprising a lower portion 2 and an upper portion 3 which are cemented together at their interengaging peripheries by suitable fusible material indicated at 4 in Figs. 2 and 5. The lower portion 2 of the base 1 is provided with a recessed reservoir 5 for containing the ink pool into which the dip pen is adapted to be inserted. The upper peripheral edge of the recessed reservoir 5 is beveled as indicated at 6 which allows the angularly disposed wall of the integrally molded pen receiving socket 16 to extend downwardly into the recessed reservoir 5 without obstruction. The lower base portion 2 is provided with an annular ledge 7 within the limits of which the recessed reservoir 5 is formed and above which the peripheral shoulder 8 on the lower portion 2 of the base projects.

The upper portion of the base 3 is provided with an annular depending wall 9 which telescopically engages within the peripheral shoulder 8 and extends toward the annular ledge 7. The upper portion 3 of the base is provided with a central circular top 10 from which there depends a central cylindrical portion 11. The central cylindrical portion 11 is recessed as indicated at 12, the recess 12 terminating in a shoulder 13. The internal bore of the central depending cylindrical portion 11 is screw threaded as indicated at 14 for receiving screw threads 23

formed on the neck of the ink bottle 22 in the inverted position illustrated in Fig. 2. The upper portion of the base 3 is provided with an integrally formed vent 15 serving as a pressure equalizing port in the hydrostatic operation of the desk set. The dip pen receiving socket is formed integrally with the upper portion of the base 3 as represented at 16. The pen receiving socket projects upwardly from the upper portion 3 of the base as indicated at 17 for receiving the dip pen which I have shown generally at 26. The pen receiving socket 16 comprises the upwardly projecting integral portion 17 which is substantially frusto-conical in shape, the cylindrical portion 19, the frusto-conical portion 20, and the restricted cylindrically apertured portion 21 through which the pen point 30 of the dip pen is adapted to be projected. The pen holder 26 has a peripheral extremity 27 thereon and a rounded end portion 29 spaced therefrom by means of the interposed cylindrical portion 28 of the pen holder. The rounded end portion 29 and the peripheral extremity 27 of the pen holder coact to substantially close the socket of the pen guide when the dip pen is in position as represented in Fig. 2. The pen receiving socket is thus substantially closed at all times when the pen holder is not being carried in the hand of the writer. Accordingly, dust and foreign matter are excluded from the pool of ink 31 in the recessed reservoir 5.

The ink bottle 22 has the screw threads 23 thereof engaged with the integrally formed screw threads 14 in the upper portion 3 of the base. A peripheral abutment 23a on the neck of the ink bottle serves as a stop for supporting the ink bottle 22 with respect to the shoulder 13 in the central recess 12. The neck of the ink bottle 22 has a restricted aperture 24 therein through which a restricted flow of ink under hydrostatic pressure is supplied to the pool of ink 31 from the supply of ink in the bottle 22. A suitable protective and ornamental cover 25 is provided over the ink bottle 22. To facilitate the mounting of the desk set on a supporting surface, I may provide adhesive pads shown generally at 32.

In the manufacture of the desk set shown in Figs. 1-6, the lower portion of the base 2 is telescopically fitted about the annular depending wall 9 with the fusible material 4 therebetween. The parts thus prepared are subjected to a fusing and baking operation which results in the fusing of a substantial joint between upper portion 3 and lower portion 2 of the base. This joint is substantially invisible. When the base is dipped or sprayed or otherwise coated with ornamental glaze or pigment, the joint becomes wholly invisible and the base appears as a single unitary member. A pleasing and esthetic appearance is provided because a streamlined effect is obtained by ornamenting the surface of the upwardly projecting integral wall 17 of the pen receiving socket, which ornamented surface continues without interruption throughout the entire cylindrical side wall of the base 1.

In Figs. 7-10, I have illustrated a modified form of the desk set of my invention in which the upper portion of the hollow molded base is formed from a molding illustrated at 39. The molding 39 has a downwardly depending skirt 40 which is strengthened in spaced angular positions by vertically extending ribs 41. The ribs 41 provide supports for embedded tubular inserts 42 which are screw threaded for receiving

screws 43 which pass through lower closure plate 44 forming the bottom of the desk set. The hollow molded base 39 is strengthened transversely by means of the substantially radially extending ribs 45. The hollow molded base 39 is also provided with an eccentrically positioned annular recess 46 having a pair of depending wall portions 47 projecting from beneath the base 39. An annular gasket 48 is seated in the annular recess 46 and provides a seal for the upper peripheral edge 49 of the ink receptacle 50. The ink receptacle 50 is thus supported eccentrically within the hollow molded base 39 in a position for supplying ink to the point of the dip pen 26 inserted into the pen receiving socket 16' as delivered from the ink supply bottle 22 through restricted aperture 24. In order that parts of the form of my invention illustrated in Figs. 7-10 may be readily compared to the corresponding parts shown in Figs. 1-6, I have applied primed reference characters to the corresponding parts. That is to say, integrally formed pen receiving socket is shown at 16' having upwardly projecting integral wall 17' including frusto-conical shaped wall portion 18', cylindrical shaped wall portion 19', frusto-conical shaped wall portion 20', and aperture 21' in the end of the pen receiving socket 16'. The pool of ink 31' is replenished hydrostatically from the ink supply bottle 22 through restricted orifice 24 for supplying ink to the dip pen point 30. The screw threads 23 of ink bottle 22 are engaged with screw threads 14' in the central depending cylindrical portion 11' in central recess 12', the peripheral flange 23a of the ink bottle resting against the shoulder 13'. The pressure equalizing vent is molded in the base 39 as represented at 15'. The adhesive supporting feet for mounting the desk set on a supporting base are indicated at 32'.

The assembly of the desk set of the form illustrated in Figs. 7-10 is very simple in that it is only necessary to locate the receptacle 50 in the eccentric position with the peripheral edge 49 thereof seated against gasket 48 and then apply closure 44 by means of screws 43 to the underside of base 39, whereupon the assembly is complete. The relatively small quantity of ink in receptacle 50 insures the efficient operation of the desk set and conserves the ink supply, at the same time preventing deterioration and evaporation of the ink.

In the form of my invention illustrated in Figs. 11-14, the upper and lower portions of the base are molded from synthetic material having a substantially cylindrical contour forming a telescopic engagement and presenting a pleasing external appearance. The upper portion of the base has been designated at 33 having a depending cylindrical skirt 34. The lower portion of the base is indicated at 35 having an upwardly extending cylindrical wall 36. The cylindrical wall 36 and skirt 34 are united by a suitable cement or glue 37. The lower portion of the base is provided with an integrally molded receptacle 38 which is eccentric with respect to the central axis of the lower portion of the base 35. This receptacle 38 provides a container for a restricted pool of ink shown at 31'' which conserves ink consumption and protects the ink against evaporation and deterioration. In order that the parts of the structure shown in Figs. 11-14 may be readily compared to the parts of the structure shown in Figs. 1-6, I have represented corresponding parts in Figs. 11-14 by

double primed reference characters. That is to say, the upper portion of base 33 is provided with central recess 12'' which contains shoulder 13'' and internal screw threads 14'' for receiving the screw threaded neck 23 of ink bottle 5. 22. Correspondingly, the pen receiving socket which is molded integrally with the upper portion of the base 33 is indicated at 16'' for receiving the dip pen 26. The pen receiving socket 16'' includes integrally molded upwardly projecting wall 17'', frusto-conical shaped portion 18'', cylindrical portion 19'', frusto-conical shaped portion 20'', and aperture 21''. The pen point 30 is insertable through the aperture 21'' in the pen receiving socket 16''. The pressure equalizing port for the hydrostatic desk set is shown at 15'' in the upper portion of the desk set indicated at 33. The adhesive supporting feet for the desk set illustrated in Figs. 11-14 are indicated at 32''. 20

The assembly of the desk set constructed according to Figs. 11-14, is very simple as it is only necessary to telescopically engage the lower portion of the desk set 36 with the upper portion of the desk set 33 and apply the cement 25 or glue 37 therebetween to effect a rigid assembly of the hydrostatic unit.

In all forms of my invention, the screw threaded end of the ink bottle is engaged in the screw threads molded into the upper portion of 30 the base structure to a position in which the flange on the ink bottle abuts with the shoulder on the upper portion of the base structure. The cylindrical cover member is then inserted over the ink bottle 22 and the hydrostatic desk set is 35 ready for operation. Because of the relationship of the pen receiving socket with respect to the pool of ink below the restricted orifice of the ink supply bottle, a continued supply of ink may be depended upon into which the point of the 40 dip pen is inserted from time to time during writing operations. The pressure equalizing port 15 insures a continuous supply of ink from the ink bottle to the pool beneath the restricted orifice 24 under control of hydrostatic pressure. 45

I have found the improvements of my invention highly practical and efficient in operation but I realize that modifications may be made and I intend no limitations on the invention except as may be imposed by the scope of the appended 50 claims.

What I claim as new and desire to secure by Letters Patent of the United States is as follows:

1. A desk set having a base structure formed by a pair of coacting, coextensive and interengaging members, one of said members having means for supporting an ink bottle in inverted position and having a dip pen guide extending therethrough, the other of said members having a container for ink formed integrally therewith 55 eccentric with respect to said base structure and having an area substantially less than the area of said member, said container providing a pool for ink delivered by the inverted ink bottle for supplying ink to a dip pen inserted through said 60 dip pen guide.

2. A desk set comprising a base structure constituted by a pair of coacting, coextensive and telescopically engaged base members, one of said base members providing a support for an ink 70 bottle in inverted position and having a dip pen guide formed adjacent thereto, the other of said members including a container for a pool of ink disposed beneath the delivery end of the ink bottle, said container being restricted in size with 75

respect to the size of said member for confining the supply of ink from said ink bottle to the point of a dip pen inserted through said dip pen guide to a restricted area, and said container being mounted eccentrically with respect to said base member.

3. A desk set comprising a base structure formed by a pair of coacting, coextensive and telescopically arranged interengaging members, one of said members providing a support for an ink bottle in inverted position and providing a dip pen guide adjacent thereto; the other of said members having a supplemental chamber formed therein bridging the gap between the dip pen guide and the inverted ink bottle opening for confining a supply of ink for the point of a dip pen immersed in said dip pen guide to a restricted area, the level of ink in said chamber being substantially below the rim of said chamber.

4. A desk set comprising a substantially hollow base structure, means disposed centrally of said base structure for supporting an ink bottle in inverted position, a dip pen guide supported by said base structure and extending into the hollow portion of said base, and a receptacle for ink supported beneath said hollow base structure and extending between the terminus of said dip pen guide and the discharge end of the inverted ink bottle, the level of ink in said receptacle being substantially below the rim of said receptacle.

5. A desk set comprising a hollow base structure internally grooved on the lower surface thereof, an ink receptacle having its upper peripheral edge projecting into the annular groove in the undersurface of said base structure, means for supporting an ink bottle in inverted position above said ink receptacle, and a dip pen guide extending through said base structure and terminating in said ink receptacle.

6. A desk set comprising a substantially hollow inverted base structure having means for supporting an ink bottle in inverted position thereon,

a dip pen guide carried by said base structure adjacent the support for the inverted ink bottle, an ink receptacle mounted eccentrically with respect to said base structure and bridging the distance between the discharge end of the inverted ink bottle and the terminus of the dip pen guide for confining a pool of ink between the discharge end of the inverted ink bottle and the terminus of the dip pen guide, the level of ink in said pool being substantially below the rim of said receptacle.

7. A desk set comprising a substantially hollow base structure, means for supporting an ink bottle in inverted position with respect to said base structure, a dip pen guide extending through said base structure adjacent the support for the inverted ink bottle, said base structure having an annular groove therein encircling the support for the inverted ink bottle and the terminus for said dip pen guide, a receptacle for ink having an upwardly projecting peripheral edge extending into the annular groove in said base structure, and means supported by said base structure for mounting said receptacle in position.

8. A desk set comprising a substantially hollow base structure having a central support for an inverted ink bottle and a dip pen guide adjacent thereto, the undersurface of said hollow base structure being provided with a circular groove extending around the terminus of said dip pen guide and the support for the inverted ink bottle, an ink receptacle having its upper peripheral wall extending into said annular groove, sealing means between said annular groove and the edge of said upper peripheral wall of said receptacle, and a plate member extending transversely of said hollow base for supporting said receptacle in position for confining a pool of ink between the discharge end of the inverted ink bottle and the terminus of the dip pen guide.

CAREY GARFIELD GREGORY.
